UNITED STATES PATENT OFFICE.

FERNAND PHILY, OF PAU, FRANCE.

STATIONARY YARN GUIDE FOR WEAVING LOOMS.

Application filed November 10, 1925, Serial No. 68,079, and in France November 20, 1924.

The object of the present invention is a yarn guide for weaving looms by which I automatically produce loops consisting of one or more warp threads, and into which a woof thread is automatically inserted either by mechanical means or by hand, by the use of a shuttle, a simple hook or any other suitable device.

Yarn guides such as contemplated by the 10 present invention may be used in various types of fabric looms, and are particularly adapted to looms of the construction disclosed in my co-pending patent application Serial Number 68,080.

15 In comparison with known yarn guides, I obtain the advantage of holding the two threads, warp and woof in an approved manner until the final loop or knot is completely formed, and also of guiding the latter out 20 of the yarn guide and along the latter until it reaches the previously formed loops or knots. Due to the special shape of my said yarn guide, it will protect the warp against the devices used for inserting the woof 25 through the latter, since it is constructed so as to comprise an outlet channel, almost closed, which offers passage only to the woof thread when the loop or knot is being formed.

30 The said invention is shown in the appended drawings which are given by way of example.

Fig. 1 is a side view of the yarn guide.

Fig. 2 a front view, and Fig. 3 a plan 35 view.

Figs. 4 to 13 show the various stages of the formation of a loop. Fig. 14 shows a yarn guide in which two warp threads are placed.

40 Figs. 15 to 17 show another method of making a loop.

Figs. 18 to 23 show the rows of loops or knots obtained with the said yarn guide.

Fig. 24 shows a second constructional form 45 of a yarn guide.

As observed in the drawings, the yarn guide consists of a metal plate 1 whose front part has a shape which is suitable for the work to be performed; 2 is an aperture for 50 the insertion of the shuttle and the placing of the woof thread 3. The horizontal part 4 of said aperture serves to close the space above the woof thread so that it cannot leave its proper part, and it also serves to 55 protect the warp thread or threads 5. In

addition to the use of the said horizontal part, the aperture is bounded by an inclined part 6 which allows the woof thread to rise into the horizontal output slot 7, whereby the woof thread will be guided until the 60 loop is completely formed; 8 and 9 are eyes for the insertion of the warp 5, and the number of such eyes is optional. In Fig. 1 it will be noted that the distance between the eye 8 and the end 10 of the yarn guide 65 somewhat exceeds the distance between the eye 8 and the point 11, so that when a loop is completed and is brought to the point 11, to allow the formation of another loop, it will be prevented from jamming against the 70 rear part 12 of the yarn guide and chiefly at 11. But this arrangement is not essential, and the front part of the yarn guide can be so disposed that the distance between 8 and 10 is the same as between 8 and 11. But in 75 this event care must be taken, during the formation of the loop, that it be pushed beyond the point 10 so that the distance from the eye 8 to the loop shall exceed the distance from the eye 8 to the point 11. 80

The formation of the loops by means of the said yarn guide is as follows:

In the yarn guide (Fig. 4) is threaded a warp thread 5 leading from a roll of warp thread, a bobbin or the like which holds the 85 same; it is unwound automatically or by means of a drawing roller, as the loop is formed.

The warp thread is inserted first into the eye 9, passes to the other side of the guide, 90 and then rises and passes through the eye 8, thus returning to the front in order to form the loop.

In Fig. 5 it is observed that the loop has been formed and that it has a triangular 95 shape. When the warp thread is in this position, the woof thread 3 is inserted through the middle of the loop, and as above stated by means of a shuttle or a hook, and either by hand or by mechanical means. 100

The end 14 of the warp thread is now caused to move by suitable means whereby it oscillates about the curved part of the guide. The radius of this part increases from the point 10 onward taking the point 105 15 as a centre.

In Fig. 6, the loop formed by the warp thread closes upon the woof thread 3.

In Fig. 7, the loop is completely closed 110 upon the woof thread, and the latter has

2
moved forward upon the inclined part 6 of the guide.

Fig. 8 shows the loop formed; it has now entered the output slot 7 and the woof thread 5 slides on the edge 16 so as to obtain the position of Fig. 9 and thence the position of Fig. 10. The loop is now finished and is outside the yarn guide. During the formation and the movement of the loop, the warp 10 thread unwinds from its bobbin by a sufficient length to allow the loop to leave the position of Fig. 10 and to take the position of Fig. 11. In Figs. 8, 9 and 10, it is further noted that the preceding loop runs very 15 close to the curve of the guide comprised between the points 18 and 10. To push the woof thread 13 forward or out of the guide, I preferably employ a reed which is actuated by suitable means.

20 Fig. 11 shows the warp thread which after having formed the loop will now return to the rear and will assume—after passing through position 12—the position shown in Fig. 13 which corresponds to that of Fig. 5. 25 All the movements for forming the loop are now completed and a new loop may now be formed.

Fig. 14 shows a yarn guide into which 30 there are inserted two warp threads 5, one on either side; I thus obtain by the same movements and with a single yarn guide two loops or two torsions at the same time around the woof thread, one to the right and the other to the left.

35 With my said device I am enabled to move the warp thread 5 in the direction opposite the side at which it was threaded, so that I obtain loops whose torsion is contrary to what the yarn guide will afford in a regular 40 manner. This operation can be effected by hand or by means of a needle adapted to move the yarn, or by like means.

Fig. 16 shows a second position of the yarn thus moved, and Fig. 17 shows the position 45 in which the warp has formed its triangular loop for the insertion of the woof 3.

By this latter method I am enabled to interlace between the already-formed regular loops, the loops whose torsions have the 50 opposite direction relatively to the other loops, thus producing a fabric having a varied appearance.

Figs. 18 and 19 show loops which have been regularly formed, i. e. according to 55 Figs. 4 to 13, and Figs. 20 and 21 show their position when completed.

Fig. 22 shows the loops obtained by the

method according to Figs. 15 to 17, mingled with the regularly obtained loop.

Fig. 23 shows the position naturally assumed by the loop of Fig. 22 according to the tension which is given them; these loops may be mingled one at a time or by regular or irregular groups.

Fig. 24 shows a second form of yarn guide 65 in which the part above the aperture and slot is eliminated; the said guide devices may be juxtaposed in suitable number according to the width of the fabric to be produced.

I claim:

1. A stationary yarn guide in which warp and weft threads are to be looped together, comprising a body portion having warp thread receiving means and weft thread receiving means, and guiding means to guide both threads throughout the time of loop formation.

2. A stationary yarn guide in which warp and weft threads are to be looped together, comprising a body portion having spaced eyes designed to have a warp thread threaded therethrough, an aperture in the body designed to receive a weft thread, and an elongated slot in the body communicating with the aperture and designed to guide the warp and weft threads until the loop therebetween is completed.

3. A stationary yarn guide in which warp and weft threads are to be looped together, comprising a body portion having spaced eyes designed to have a warp thread threaded therethrough, said body portion having an angular aperture the upper wall of said aperture being straight and the lower wall inclined, and said body portion having a straight guide slot communicating with said aperture.

4. A stationary yarn guide in which warp and weft threads are to be looped together, 100 comprising a flat member consisting of an elongated shank and a substantially semicircular body, said body having an angular aperture therein and a guide slot leading from said aperture outwardly to the edge of the body, an eye in the body adjacent its lower curved edge, and a second eye in the body on a higher plane than the first mentioned eye, said second mentioned eye being spaced a greater distance from the front of the semicircular body than from the rear thereof.

Signed at Lyon, France this 28th day of October A. D. 1925.

FERNAND PHILY.
